Application March 7, 1942, Serial No. 433,757

16 Claims. (Cl. 178—7.2)

This invention relates to synchronizing and phasing electrical circuits and, in particular, to a method and apparatus for synchronizing and phasing television equipment.

In television practice it is usual at transmitting stations to transmit, in addition to the video signal, synchronizing signals so that the picture to be reproduced at the receiver may be stabilized by the transmitted signals. In order to avoid irregularities in the scanning raster, it is customary at the transmitting station to synchronize the generator of synchronizing signals, normally called the synchronizing generator, with the 60-cycle per second supply which furnishes power to the system. Conventionally, this is done by utilizing a master oscillator whose frequency is a multiple to that of the line frequency of the scanning pattern and to produce electrical wave energy whose frequency is 60 cycles by a system of electrical dividers from the master oscillator. The produced 60 cycles per second is thereafter compared with the 60-cycles per second energy of the supply mains and the difference between the two is utilized to control the frequency of the master oscillator in such a direction as to either increase or decrease the master oscillator frequency until the frequency supplied at the output of the dividers is identical with that of the 60-cycle supply main. This insures that the transmitted synchronizing signals are always in synchronism with the 60-cycle supply main. Such apparatus is well known in the art and one form widely used is described in detail in a paper by Smith and Bedford which appeared in the RCA Review for July, 1940, vol. 5, #1, pages 51-68, "A Precision Television Synchronizing Signal Generator."

Such a system is perfectly satisfactory where only a single transmitting chain is used or where programs originate only at a single point. When, however, programs originate from a remote point and are sent to the main studios for retransmission, then it becomes desirable to supply some means for locking in the synchronizing generator at the remote point with that at local or main station. This feature is desired because the remote pick-up equipment may be operating on a different 60-cycle supply from that of the main studios. Switching, therefore, from the remote program to that of the main studio, or vice versa, results in an abrupt change in phase and frequency of the synchronizing signal with the result that at the receiver the picture drops out momentarily, since the receiver can not accom-

modate an abrupt change in phase and frequency of scanning of the received signals.

Moreover, in the transmission of special effects, such as "lap dissolves" or composite pictures by superimposing of two or more cameras, it is necessary to insure synchronism and proper phasing of each individual camera chain with each other. This is necessary to prevent any blurring arising from the drifting of one picture past the other in the case of superimposed pictures and to insure that no displacement between the pictures occurs in the "lap dissolve."

My invention provides both a method and apparatus for insuring synchronism between master oscillators or master synchronizing generators so that no "tearing out" of the picture at the receiver is produced and to insure proper operation for "lap dissolves" and composite picture transmissions. Briefly, my invention utilizes the synchronizing signal from one of the generators to produce a source of synchronizing wave energy which may be shifted in phase and which is supplied to the other of the synchronizing generators to control its frequency, in lieu of exercising control of the second synchronizing generator by the 60-cycle supply main. It should be appreciated that not only is it necessary to control the second oscillator with respect to frequency but that it is also necessary that the second oscillator be maintained in phase with the first oscillator.

In this respect it is not only necessary that the line synchronizing signals be maintained in phase but that the vertical synchronizing signals likewise be in phase. In addition, since double interlace scanning is generally provided, it is necessary that the vertical synchronizing signals be in phase for the proper field. It will be understood that a vertical synchronizing signal from one of the generators could be superimposed upon the vertical synchronizing signal of a second generator which would indicate proper phase and yet result in an improper transmission, since the first vertical synchronizing signal may be that which follows the scanning of the odd field while the vertical synchronizing impulse of the second generator may be that which follows the scanning of the even field. It will thus be clear that it is necessary that the two synchronizing signals coincide following the scanning of the same relative field, that is to say, that they must coincide following the scanning of the odd fields, as well as the even fields. Provision is made for insuring this feature by my method and apparatus.

Moreover, in order to safeguard against oper-

ational difficulties, means are provided for returning the control of one of the generators to the local 60-cycle supply in the event that the synchronizing signal derived from the other source should fail. It is thus the main object of my invention to provide a new and improved method and apparatus for synchronizing electrical circuits.

Another object of my invention is to provide a new and useful method and apparatus for synchronizing the synchronizing generators of a television transmission system.

Another object of my invention is to provide a new and useful method and apparatus for maintaining the synchronism and phasing of a plurality of television synchronizing generators with the additional feature of supplying an alternative control in the event that synchronizing signals from one of the generators should fail.

Another object of my invention is to provide new and improved synchronizing method and apparatus which permits the selection for transmission of one or more individually generated video signals without producing "drop-outs" or "tearing" of the received image.

Still another object of my invention is to provide a method and apparatus for synchronizing generators to give improved "lap dissolve" and superimposed or composite picture effects.

Other objects of my invention will become clear upon reading the following detailed description taken together with the drawings.

In the drawings, Figure 1 shows in block diagram form an overall television system wherein provision is made for transmitting from a main transmitting point programs originating from different sources; Figure 2 shows in block diagram form a portion of the system with further details; Figure 3 shows in block diagram form the details embodying my method and apparatus for synchronizing different synchronizing generators with each other; Figure 4 shows a detailed circuit diagram of the phase shifting apparatus and synchronizing control circuit; and Fig. 5 is a schematic circuit to show one form of automatic control.

Turning now to Figure 1, I have shown the elements of a television system in which there is provided a studio pick-up 1, a remote unit 3 for picking up programs from the field, and a film scanner 5 for providing pictures from motion picture film. At the master control position, generally located adjacent the studio pick-up 1, is a master control selector 13 which enables the operator to select one of the three programs. The output of the selector is fed to a line amplifier 15 for suitable amplification and thereafter the signals are used to modulate the transmitter 17 for transmission in the antenna 19. Diagrammatically there is shown the synchronizing generators 7, 9, 11 for synchronizing the film scanner, the studio pick-up, and the remote unit, respectively. It will be appreciated that in practice two or more equipments may actually use the same synchronizing generator, but for purposes of illustration each of the video camera chains has been shown as being controlled by a separate generator.

It will be observed that in view of the fact that the remote unit 3 and the film scanner 5 are controlled from different synchronizing generators, that when the switching operation takes place at the selector 13, the transmitted signals, received at the antenna 21 and rectified

at the receiver 23, actuate the reproducer 25 with an abrupt change in the relative timing of the synchronizing impulses, since, in general, the synchronizing generators 7, 9, 11 will not be supplied from the same power supply. Moreover, even if the three synchronizing generators were supplied from the same power supply, due to the different times of transmission and different time constants of the locking circuits for the remote unit 3 as compared with that of the studio pick-up 1, the line synchronizing signals will be displaced with respect to each other. At the receiver there would result a "tearing out" of the picture, since the receiver blocking oscillator can not follow the appropriate change in phase displacement of the two synchronizing signals following the switching operation. To avoid the "tearing out" of the picture with a resultant deterioration of reception, it is necessary to provide some means of so synchronizing the various pick-up points with each other such that the switching operation will not disturb the line synchronizing signals. With such provision being made, it will readily be appreciated that no "tearing out" of the picture will take place at the reproducer 25, since the receiver 23 is unable to determine the time that switching is taking place. While the difficulty induced by the different times of transmission through the various chains may be overcome by using a circuit arrangement shown schematically in Figure 2, this arrangement does not solve the problem entirely.

It will be noted in Figure 2 that the synchronizing generator 31 serves to synchronize the film scanner 33 and the studio pick-up 35, while the synchronizing generator 41 serves to synchronize the remote unit 43. Between the film scanner 33 and the selector 35 is provided a phase shifter 37. Similarly, between the remote unit 43 and the selector 33 there is provided a phase shifter 45. By appropriate adjustment of the phase shifters 37 and 45, assuming no drift between the two line frequencies, the total transmission time through the chains can be adjusted so as to be equal to the time of transmission through one of the chains or equal to the time of transmission through one of the chains plus an integral number of frame time intervals. Under these conditions both the line synchronizing and vertical synchronizing impulses will have the same relative phase position. It must be noted that the phase position is important, since in an interlace system it would be possible to have the frame synchronizing signal of an even field coincide with the frame synchronizing signal of an odd field, and under these conditions the reproduced picture would suffer from misynchronization. In addition, because the synchronizing generators 31 and 41, in general, run from different power supplies, there is no assurance that they would be of the same frequency and again mis-synchronization might take place. To avoid this mis-synchronization, I have provided by my invention the method and means of deriving from one of the camera chains synchronizing impulses which are used to control the synchronizing generator of a second chain. This provision locks the two synchronizing generators together so that the emitted signals, regardless of the switching position, always transmit line and field synchronizing impulses which have the same relative phase position. This enables rapid switches to be made without destroying the

quality of the program by having the picture drop out momentarily or to tear out.

In Figure 3 I have shown somewhat more detailed the features of my invention which provide the stability of operation which is so desirable when transmitting a mixed program or composite pictures. For purposes of illustration, I have assumed that there is a remote unit 53 synchronized by its generator 51 and transmitting the combined video and synchronizing signal through antenna 55 to a receiving antenna 57. The receiving antenna is considered to be located in the proximity of the studio equipment 73. The signals from the antenna 57 are rectified by the receiver detector 59 and the output is fed over two paths, one running to the switching position 85-87 to be passed on to the line amplifier and subsequent equipment for transmission. A portion of the output travels over a second path to a D. C. inserter 61. The D. C. inserter 61 may be of any of the conventional D. C. inserters, such as are well known in the art and generally embodying a diode connected across the grid cathode circuit of a thermionic amplifying tube to reinsert the direct current component representative of the average brightness of the picture which is generally suppressed during the transmission. The reason for inserting the direct current component is to counteract the effects of any inadvertent low-frequency noise or hum which may be picked up during the transmission and reception of the signal. The output of the D. C. inserter is fed to the skimmer 63 which is a threshold amplifier which tends to give zero output for all signals supplied to it below a certain predetermined value and which gives substantially constant output for all signals exceeding the said predetermined value. The threshold level corresponding to the predetermined value is generally set to operate only upon the receipt of the synchronizing signal. The skimmer therefore serves to separate the synchronizing signal from the picture signal, assuming blacker-than-black transmission, and the limiting feature of the skimmer, when taken together with the D. C. insertion, serves to counteract any fading which may have been present so as to insure stability of synchronization. The output of the skimmer 63, it will be appreciated, will therefore have the wave form of square-top waves. These waves are then passed to a wave shaper 65 which converts the square waves to substantially a sinusoidal wave. The sinusoidal wave output of the wave shaper 65 is thereafter fed to a phase splitting network 67. The purpose of the phase splitting network is to produce a three-phase sinusoidal output from the single phase energy and this is accomplished by a number of parallelly connected reactance circuits so chosen as to give at the output of each arm a sinusoidal wave spaced 120 degrees from its adjacent reactance arm. The three-phase output of the phase splitter 67 is thereafter fed to a phase shifter 69, and for the purposes of my invention, I have provided a Selsyn motor type of phase shifter. This type of phase shifter is extremely desirable since by continuous rotation of the Selsyn motor rotor the phase angle can be made as large as desired, whereas the single phase type of phase shifter which can be conveniently used has a restricted maximum angle of phase shift. The output of the phase shifter 69 is thereafter fed to a frequency doubler 71 for the purpose of

doubling the frequency of the sinusoidal wave passed through the phase shifter 71. The output of the frequency doubler may be fed through the switch 91 to the local synchronizing generator 75 to synchronize the master oscillator thereof, which is assumed to run at double line frequency.

The studio pick-up equipment 73 is synchronized by its local synchronizing generator 75. The generator 75 may be controlled through the switch 93 from one of the two 60-cycle supplies 83 and 79. Under ordinary circumstances the switch 95 is thrown to the position 99 so that the 60-cycle supply 83 is fed through the switch 93 to the synchronizing generator 75 to control the frequency of the master oscillator by means of a differential biasing circuit. One form of a differential biasing circuit that may be used is that described in considerable detail in the above referred to publication by Smith and Bedford. A phase shifter 81, which may take any form, but for simplicity in practice is usually a Hartshorn circuit, is provided in order to facilitate the initial adjustment of the differential biasing circuit. The phase shifter 81 may also be activated by remote control from a film studio, for example, in order to properly phase the film scanner with the film projector which also operates on the 60-cycle supply. When the switch 95 is thrown to the position 97, then the three-phase 60-cycle supply 79 serves to control the synchronizing generator 75. The phase shifter 77 of the Selsyn motor type provides means for obtaining as large a phase shift as desired, since each revolution of the rotor of the Selsyn motor adds 2 radians, since the number of revolutions which may be made is unlimited. It will be readily appreciated that the phase angle may be made any desired value, which is not true of the phase shifter operated at 81, since the Hartshorn circuit only provides a phase shift of 180 degrees. It will be appreciated, therefore, that the phase of the vertical synchronizing pulse will be determined by the settings of the phase shifter 77 or 81, and, moreover, aids in reducing the amount of phase shift necessary to be introduced by the phase shifter 69.

It will be appreciated that to shift synchronizing control from one of the local supplies to that of the remote unit by opening the switch 93 and closing the switch 91, it is exceedingly difficult to make the switching operation at precisely the right instant to cause the generator 75 to lock in on the right line because the impulses from the frequency doubler 71 and those of the synchronizing generator drift by each other. Thus, some shifting of the phase of the controlling double frequency pulses will be required in order to line up perfectly the two generator outputs. The maximum correction which would be required is a shift comparable to the number of lines in one field, which occurs when vertical impulses are perfectly lined up with each other, but, in one case, the first equalizing pulse starts one line after the leading edge of the preceding horizontal pulse, while, in the case of the other generator, the first equalizing pulse occurs one-half line after the leading edge of the preceding horizontal pulse, that is to say, the even fields from one source and the odd fields from the other source have their vertical synchronizing pulses matched. To correct for this condition in a 525-line picture, for example, requires a phase shift of 262½ lines, or 189,000 degrees in terms of the double frequency controlling pulse.

Hence the Selsyn motor continuous phase shift arrangement.

This extreme condition can be avoided, however, if prior to the operation of the switches 91 and 93, switch 95 is thrown into position 97. By observing, through the aid of monitors, the relative position of the controlling signals from 71 and the signals from the generator 75, the phase shifter 77 may be operated to bring the two groups of controlling signals into approximate alignment, i. e., 2π radians of rotation on phase shifter 77 is the equivalent of $262\frac{1}{2}$ times 2π radians of rotation on phase shifter 69. Following this, the opening of the switch 93 and the closing of the switch 91 can be effected, and the maximum amount of correction needed will then be only on the order of 3 or 4 lines. Correction by rotating the phase shifter 69 is not noticeable by the observer, except insofar as the received picture is free from "tearing-out" effect when the switch is made. The use of the three-phase 60-cycle phase shift will be understood in the light of the operation of the system when film transmission is used in addition to the studio pick-up 73. In the case of film transmission, the local generator must be synchronized with the local power supply and a certain amount of phase shift is needed to properly align the generator pulses with the frame lines on the film. If the phase shifter 81 were used to align the generator 75 with that of the generator 51, the phase shifter 81 would have to be returned to approximately its normal position each time after the two generators were disconnected from each other in order to insure the film scanner having proper phase relation with the film projector. From the operational point of view, it is preferable to supply a supplementary phase control so that when the local generator 75 is released from remote control, it can be immediately placed in position for film transmission by the operation of a switch rather than having to set carefully the control to a predetermined position. Moreover, the supplementary 60-cycle phase control 77 has a large enough phase shift to correct easily and quickly for any previous misalignment condition of even fields with one generator and odd fields from the other, whereas the phase shifter 81 does not provide the range necessary to accomplish this easily.

More specifically, the method of providing the supplementary phase shift is shown in Figure 4, together with a more detailed showing of the phase splitting network 67, the phase shifter 69, and the frequency doubler 71 of Figure 3. In Figure 4 the 60-cycle supplies 172 and 186 correspond to the supplies 78 and 83 of Figure 3. The three-phase supply connected to the terminals 172 are fed to three transformers 173, 175, 177, which have their primaries each tied between one side and neutral.

The secondaries, for the purpose of illustration, are shown connected in delta, the sides 179, 181, 183 corresponding to the three windings of a Selsyn stator. The rotor 185 of the Selsyn motor is grounded at the mid-tap and the outer terminals connect to the contacts 193 of the switch 189. The 60-cycle supply fed to the terminals 186 corresponding to the 60-cycle supply 83 of Figure 3 is fed through a transformer 187 to the terminals 191 of the switch 189. The output terminals of the switch 189 connect to a phase shifter comprising the serially connected condenser 195 and variable resistor 197, the phase shifter being of the Hartshorn

type well known in the art. The circuit comprising the diodes 199 and 201 and the time constant circuit 203 and the transformer 204 and condenser 207 comprise the differential biasing circuit, the transformer 204 being fed on the primary side with 60-cycle pulses derived from the frequency divider of the synchronizing generator. This circuit is shown and described in detail in the above referred to publication by Bedford and Smith. It will be readily appreciated, therefore, that the differential biasing circuit, by throwing the switch 189 either in the first position, or second position will utilize the 60-cycle supply fed to the terminals 181 or the three phase supply connected to the terminals 172 as a standard against which the impulses fed to the transformer 204 are compared. The output of the differential biasing circuit is fed to the grid 171 of the tube 167, which tube serves as the frequency control tube of the double line frequency master oscillator tube 168 by being connected across the resonant circuit of the oscillator.

To control the master oscillator tube 168 directly, sinusoidal wave energy of horizontal line frequency is fed to the terminals 101. This horizontal line frequency energy is derived, as explained in connection with Figure 3, from the output of the wave shaper 65. The energy fed to the input terminals 101 is then fed to three parallel paths, each path constituting one phase of a three-phase phase splitter. The energy from 101 is first of all fed to the tube 121 by means of capacity resistance coupling. The value of capacity of the condenser 113 is made very large, while the resistance 115 across the grid circuit of the tube 121 is likewise made large. Since the line frequency is relatively high, substantially no phase shift, or at most only a very little phase shift, takes place in the voltage across the grid 40 of the tube 121 compared with the voltage fed in the terminals 101, the condenser 103 also being a very large value. The output of the tube 121 is fed to the delta winding 129 of the Selsyn motor 45 127.

The input voltage is likewise fed to the tube 119 through capacitor 109 and across the resistor 111. The capacitor 109 and the resistance 111 are so chosen as to introduce a phase shift of voltage 50 which leads the input voltage by substantially 60 degrees. The output of the tube 119 is thereafter fed to the tube 125, the output of which is likewise connected to the delta winding 129.

Tube 117 is fed with energy from the input 55 through the resistor 105 across the condenser 107. The resistor 105 and condenser 107 are so chosen as to produce a voltage which lags the input voltage by substantially 60 degrees. The output of the tube 117 is then fed to the tube 60 123, the output of which is connected to the delta winding 129. It will be noted that because the output of the tube 121 is fed directly to the delta winding, while tubes 117 and 119 have an inverting stage connected between them and the delta winding, that the additional tube introduces a further shift of 180 degrees. The result is that across the delta winding there will appear three voltages spaced 120 degrees from each other, which is required for three-phase operation. The rotor 131 of the Selsyn motor 127 will therefore supply a sinusoidal voltage whose phase angle compared with that of the energy supplied at the terminals 101 will be determined by the relative mechanical position of the rotor 131 with respect to the stator 129. Rotation of the rotor

131 will therefore increase the phase angle or decrease the phase angle, dependent upon the direction of rotation.

Across the stator 131 a potentiometer 133 is provided to supply energy of controllable amplitude to the tube 135. The amplified energy from the tube 135 is fed to a symmetrical clipper comprising the tubes 137 and 139. The symmetrical clipper tubes operate by being biased to cut-off and overdriving the grid circuits of the tubes, as is well known in the art. Under these conditions, non-linear amplification takes place with the result that one side of the output energy wave has substantially a flat top. Passing this wave through a second stage, as 139, flattens out the other side and by an appropriate adjustment of the circuit constants, the resultant wave can be made symmetrical. The output of the tube 139 is fed through a differentiating tube comprising the condenser 145 and the resistance 147. By making the value of resistance 147 relatively small compared to the reactance of the condenser 145 only the high frequency components of the square wave will be passed. The result is that a sharply peaked wave is produced at the output of the tube 141, the peaks corresponding to the substantially vertical sides of the square wave. The outputs of the tube 141 are fed to the two tubes 143 and 144 which have their output circuits made common across the resistor 153. The tube 143 has its grid circuit energized from the plate circuit of the tube 141, while the grid circuit of the tube 144 is actuated by the drop produced across the cathode resistor 149 of the tube 141 so as to provide an essentially push-push stage. The common output of the tubes 143 and 144 is consequently a series of pulses which are of double frequency compared to the frequency of the pulses supplied by the output of the tube 41. The double frequency pulses across the common output resistor 143 are fed by capacity resistor coupling to the terminal 163 of the switch 159. When the switch 159 is thrown in position to make contact with 161, the double frequency impulses are fed directly to the grid circuit of the double line frequency master oscillator tube 168. It will be noted that under these conditions the output from the tube 201 and condenser 207 is short-circuited so that the frequency control tube 167 becomes inactive to control the frequency of the master oscillator 168. When the switch is, however, thrown to the position 163, then the output from the tubes 143-144 is short-circuited and bias from the tube 201 and condenser 207 is fed to the control grid of the tube 167 to control the frequency of the master oscillator.

In order to facilitate an understanding of the operation of the frequency doubler I have shown, above each tube, representative plate circuit wave shapes to indicate the output of each of the tubes. Thus, the output of tube 135 is shown as a sinusoidal wave at 211, while the output of the tube 137 has a wave form shown in 213 in which one side is flat and the other is sinusoidal. The output of tube 139 is shown as a square wave at 215, while the output of the differentiating tube 141 shows the peaked impulses produced whenever the voltage changes appropriately, and, finally, the output appearing across the common resistor 219 in which the negative pulse of 217 is inverted. It will thus be appreciated by manipulation of switch 159 control may be had either locally from one of two 60-cycle supplies or by

the remotely generated synchronizing signals fed from the frequency doubling tubes 143-144.

It also is desirable to provide means for automatically returning the equipment to local control in the event that the remote signals are controlling the synchronizing generator and the remotely generated synchronizing signals are interrupted by reason of a failure. One means of providing such automatic control is shown schematically in Figure 5. In Figure 5 relay 289 normally has one of its armatures 297 in contact with contact 295, which short-circuits the output from the frequency doubler 271, the equivalent of the common output from the resistor 153 in Figure 4. The local control output from the tube 201 is connected to the contact 293. Contact 291 is connected to the relay winding and also to a push-button 285 which is normally open. Connected between ground and the contact of the push-button 285 is a local battery 287. The armature 283 is normally held open, and is connected through a push-button 281, which is normally closed. The push-button in turn is connected to the cathode of tube 271, whose plate is connected to a battery 279, one side of which is grounded. The grid circuit includes the bias battery 275, so that tube 271 is biased to cut-off, and an integrating circuit 273 comprising a resistance and a condenser. The circuit 273 is likewise fed with double frequency pulses from the frequency doubler 271. When frequency pulses from the frequency doubler 271 are present, momentary closure of the push-button 285 pulls both of the armatures 283 and 297 toward the contacts 291 and 293, respectively, through action of the local battery 287. The opening of the push-button 285 following its momentary closure, however, leaves the relay armatures in their closed position, due to the fact that current from the tube 285 now flows through the armature winding of the relay 289. The cut-off bias from battery 275 is overcome by the positive potential built up across integrating circuit 273. To switch back to local control it is only necessary to momentarily open the push-button switch 281, which breaks the holding current of the relay 289 and permits the armature 283 to open, as well as throwing the armature 297 back to the short-circuiting position 295. Likewise, any failure to receive double frequency pulses from the frequency doubler 271 removes the potential across the integrating circuit 273 so that the current of tube 271 is cut off, and consequently no current flows through the winding of the relay 289. Control is thus automatically returned to the local control energy source of the 60-cycle supply.

Various alterations and modifications of the present invention may become apparent to those skilled in the art and it is desirable that any and all such modifications and alterations be considered within the purview of the present invention except as limited by the hereinafter appended claims.

Having now described my invention, what I claim is:

1. The method of operating a television system having a remote television camera and a local television camera which includes the steps of generating master control synchronizing impulses at the local television camera, normally controlling the frequency of the generated impulses by locally generated energy, receiving composite video and synchronizing signals from the remote television camera, segregating the

ergy to control by the wave energy of double frequency, and means for controlling the operation of the local television camera by the controlled generated impulses.

10. A television system comprising a remote television camera and a local television camera, means for generating master control synchronizing impulses at the local television camera, means for normally controlling the frequency of the generated impulses by locally generated energy, means for receiving composite video and synchronizing signals from the remote television camera, means for segregating the synchronizing signals from the received composite signals, means for converting the segregated signals into control impulses, means for selectively switching control of the frequency of the generated impulses by the locally generated energy to control by the control impulses, means for controlling the operation of the local television camera by the generated impulses, and means for automatically returning the frequency control of the generated impulses to the locally generated energy upon failure to receive synchronizing signals from the remote television camera.

11. The method of transmitting composite television pictures formed by scenes picked up by a local television camera and a remote television camera which includes the steps of transmitting composite video and television signals from the remote television camera, generating master synchronizing impulses at the local television camera, controlling the operation of the local television camera by the generated master synchronizing impulses to produce video signals at the local television camera, receiving at the local television camera the composite video and synchronizing signals from the remote camera, segregating the synchronizing signal and the video signal from the received composite signals, controlling the frequency of the master synchronizing impulses by the segregated synchronizing signals, combining the segregated video signals with the produced video signals of the local television camera, and transmitting the combined video signals.

12. A television system comprising a local television camera, a remote television camera, means for transmitting composite video and television signals from the remote television camera, means for generating master synchronizing impulses at the local television camera, means for controlling the operation of the local television camera by the generated master synchronizing impulses to produce video signals at the local television camera, means for receiving at the local television camera the composite video and synchronizing signals from the remote camera, means for segregating the synchronizing signal and the video signal from the received composite signals, means for controlling the frequency of the master synchronizing impulses by the segregated synchronizing signals, means for combining the segregated video signals with the produced video signals of the local television camera, and means for transmitting the combined video signals.

13. The method of operating a television system having a remote television camera and a local television camera which includes the steps of generating master control synchronizing im-

pulses at the local television camera, normally controlling the frequency of the generated impulses by locally generated energy, receiving signalling energy from the remote point to provide local control signals, selectively switching control of the frequency of the generated impulses from the locally generated energy to control by the control signals dependent upon the energy received from the remote source, and controlling the operation of the local television camera by the generated impulses.

14. The method of operating a television system having a remote television camera and a local television camera which includes the steps of generating master control synchronizing impulses at the local television camera, normally controlling the frequency of the generated impulses by locally generated energy, generating control impulses at the remote point which are received at the local point, converting the signals received at the local point into control impulses, selectively switching control of the frequency of the generated impulses by the locally generated energy to control by the control impulses developed from the received signals, and controlling the operation of the local television camera by the generated impulses.

15. The method of operating a television system comprising local and remote television cameras which includes generating master control synchronizing impulses at the local point for all of the local cameras, normally controlling the frequency of the generated impulses by locally generated energy, simultaneously generating control synchronizing impulses at the remote point for controlling the remote camera devices, receiving at the local point the remotely generated synchronizing impulses transmitted from the remote point, converting the received impulses into controlling impulses, then selectively switching the control of the frequency of the generated master control synchronizing impulses by the locally generated energy to control by the control impulses derived from the remote source, and controlling the operation of the local camera by the said generated impulses.

16. A synchronizing control for a television system including remote and local television pick-up cameras which includes a local source for generating master control synchronizing impulses for all local cameras, means for normally controlling the frequency of the locally generated impulses by locally generated energy, remotely positioned means for generating control synchronizing impulses for controlling the remote camera devices, receiving means at the local point for receiving the remotely generated synchronizing impulses transmitted thereto from the remote point, signal converting means to develop control impulse energy from the received impulses derived from the remote source, selective switching means to control the frequency of the generated master control synchronizing impulses from the locally generated energy to a control by the control energy impulses derived from the remote source, and camera control means for controlling the operation of all local cameras by the generated impulses.

JAMES RUSSELL DE BAUN.
